SHOE AND METHOD OF MANUFACTURING
THE SAMEFred N. La Chapelle, Beverly, Mass., assignor to
United Shoe Machinery Corporation, Paterson,
N. J., a corporation of New Jersey

Application August 23, 1934, Serial No. 741,108

14 Claims. (Cl. 12—142)

The present invention relates to shoes and methods of manufacturing the same and is herein illustrated in its application to stitchdown shoes and their manufacture.

5 Objects of the present invention are to improve and facilitate the lasting of shoes and particularly the lasting of the toes of stitchdown shoes. It is a further object of the invention to provide a stitchdown shoe construction requiring 10 no temporary lasting fastenings at the toe end of the shoe.

The invention is applicable to either two-sole or three-sole stitchdown shoes and their manufacture and is herein illustrated in its application 15 to the manufacture of the two-sole construction. A three-sole stitchdown shoe made in accordance with the present invention would be provided with an insole of the same size and peripheral contour as the last bottom, and a middle sole of substantially the same construction as the extension insole herein illustrated. For convenience the term "extension sole" will be hereinafter employed in referring to both the illustrated extension insole and a middle sole of like 20 construction.

In its application to methods of manufacturing shoes, the present invention, in one of its aspects, consists in assembling on a last shoe parts including an upper and an extension sole 30 provided with a toe lasting member, positioning the lasting member above the toe end of the upper, and wiping the lasting member over the toe end of the upper in order to shape the upper to the last. In its application to the stretching 35 of the uppers of stitchdown shoes over their lasts, the invention, in another of its aspects, consists in assembling on a last shoe parts including an upper and an extension sole the upper surface of which at its toe end has the same outline as the bottom of the toe end of the last, and presenting the shoe to a pulling over machine or otherwise performing the pulling over operation whereby the upper is stretched lengthwise and widthwise of the last and has the margin at its toe end temporarily attached to the bottom of the insole. After the lasting operation, the toe lasting member remains in engagement with the toe end of the upper thereby holding it in lasted condition and obviating the use of temporary fastenings for 45 holding the upper at its toe end in lasted condition until it is permanently secured to the insole.

A feature of the invention is to be recognized in a lasted stitchdown shoe having an extension sole the toe portion of which is provided with an 50 outwardly-beveled margin which, as illustrated in the drawing, extends rearwardly of the shoe to the region of the tip line, the upper surface of the toe portion of said extension sole having the same outline as the bottom of the toe portion 55 of the last, the toe portion of the upper being

secured by fastenings, herein illustrated as a 5 sewn seam, to the beveled margin of the extension sole and turned outwardly therefrom. The toe portion of the illustrated extension sole is provided with a welt formed from the sole blank, the outturned margin of the toe portion of the upper being lasted to the bottom face of said welt while the remaining portion of the outturned margin of the upper is lasted to the top of the sole margin. 10

These and other aspects and features of the invention will now be described with reference to the accompanying drawing and pointed out in the appended claims.

In the drawing,

Fig. 1 is a perspective view of a last with the novel insole and lasting strip provided by the present invention temporarily attached to its bottom, a portion of the toe end of the insole being cut away and the lasting strip spaced from 20 the edge face of the insole in order more clearly to illustrate its construction;

Fig. 2 is a perspective view of an upper assembled, pulled over, and temporarily attached at its toe end to the margin of an insole such as that 25 illustrated in Fig. 1, the lasting strip being located substantially in the plane of the tip line;

Fig. 3 is a perspective view of the toe end of the upper after lasting;

Fig. 4 is a perspective view of the toe end of the 30 lasted upper after the pulling-over tacks have been withdrawn and the margin of the upper turned outwardly under the lasting strip;

Fig. 5 is a perspective view of the toe end of the lasted upper illustrating in section the seam 35 whereby the upper materials are secured to the margin of the toe end of the insole;

Fig. 6 is a perspective view of the toe end of the completed shoe illustrating in section the seam whereby the upper materials are secured to 40 the toe end of the insole and the through-and-through stitching whereby the welt and the outsole are attached to the margin of the shoe, and

Fig. 7 is a vertical transverse section through 45 a portion of the toe end of a shoe on its last illustrating an alternative construction.

In the drawing, an extension sole 10 embodying features of the present invention is illustrated in its application to the manufacture of two-sole stitchdown shoes. Referring to Fig. 1, the 50 extension sole 10, which in the illustrated construction is an extension insole, is illustrated in connection with an inverted last 12 to which it is temporarily attached by tacks 14. The last-engaging surface of the portion of the insole forward of the tip line has the same outline as the corresponding portion of the last bottom while the remaining portion of the insole is extended beyond the edge of the last bottom to receive the out-turned margin of the upper. The insole has 55

60

combined therewith a lasting member or strip 16 which preferably is formed from the insole blank by cutting a slit 18 in the insole blank beginning at a point in the region of the tip line 5 at one side of the blank and extending around the toe and back to the region of the tip line at the opposite side of the blank thereby severing the strip from the body of the insole blank while leaving it attached to the extended margin of the 10 insole in the region of the tip line. The slit is arranged to register with the edge of the last bottom and preferably is inclined outwardly therefrom from top to bottom in order to provide the insole with a beveled margin 22 adapted to receive 15 a seam 20 (Fig. 5) whereby the upper materials are secured to the toe of the insole. It will be seen that the inner edge face 24 of the lasting strip 16 has a bevel corresponding to the bevel provided in the edge face 22 of the insole. This 20 construction of the inner edge face of the lasting strip reduces to a minimum the frictional engagement of the lasting strip with the upper during the toe-lasting operation and thus measurably facilitates that operation.

25 In order to permit the margin of the toe end of the upper to be turned inwardly over the insole 10 while the remainder of said margin is turned outwardly, as illustrated in Fig. 2, the upper and lining have their margins severed at opposite 30 sides of the shoe in the region of the tip line. In order that the upper and lining may readily accommodate themselves to the position of the lasting strip 16 in the finished shoe, as shown in Fig. 6, the upper is severed at right angles to 35 its edge face, as indicated at 26 in Fig. 2, while the margin 28 of the lining is severed on a line extending outwardly and heelwardly from a point coinciding with the inner extremity of the cut 26 in the margin of the upper at an angle of approximately 45° to said cut.

40 The preferred method of making stitchdown shoes in accordance with the present invention consists in temporarily attaching the insole 10 to the last bottom, positioning the beveled edge face 22 of the toe end of the insole in alignment with the edge of the toe end of the last bottom and temporarily attaching the insole to the last bottom by means of tacks 14. The upper 30 is then 45 assembled on the last in any convenient manner whereupon the lasting strip 16 is bent upwardly 50 of the shoe toward the plane of the tip line. While the lasting strip is held in this position the toe end of the upper is drawn forwardly of the last between the inner edge face 24 of the lasting strip and the toe portion of the last. The 55 shoe is now ready for the pulling-over operation. Because of the construction of the insole 10 which permits the margin of the upper at its toe end to be turned inwardly and attached to the margin of the insole, this operation may be performed 60 by a pulling-over machine, if desired. The sides and heel end of the upper may now be lasted in any known manner, for example, by means of a machine such as that disclosed in Letters Patent 65 No. 1,117,087, granted November 10, 1914, on an application of Adam H. Prenzel. After the sides and heel end of the upper have been lasted the lasting strip 16 is wiped over the toe end of the upper bringing said strip from the position illustrated in Fig. 2 to the position illustrated in Fig. 3 70 and thereby shaping the toe end of the upper to the last. In its position in Fig. 3, the lasting strip is arranged to hold the toe end of the upper in lasted condition until it is permanently secured to the insole. The pulling-over tacks are now

75 withdrawn and the inturned marginal materials at the toe end of the shoe are turned outwardly into a position in which the grain surface of the upper is adjacent to the under surface of the lasting strip (Fig. 4). In order to secure the upper materials in lasted condition the shoe is presented to a sewing machine, such for example as that disclosed in Letters Patent No. 1,864,-510, granted June 21, 1932, on an application of Bernard T. Leveque. This machine is organized 10 to form a chain-stitch seam 20 (Fig. 5) and to position that portion of the seam which presents a single line of stitching in the angle defined by the outturned margin 33 of the upper and the adjacent portion of the body of the upper. An 15 outsole 32 (Fig. 6) and, if desired, a mock welt 34 may now be secured to the shoe by a lockstitch seam 36 extending through the entire thickness of the margin of the shoe.

20 In the manufacture of three-sole stitchdown shoes in accordance with the present invention an insole 38 (Fig. 7) of the same size and peripheral contour as the last bottom is temporarily attached to the last bottom. Preferably the lining 40 is lasted inwardly over the margin of the 25 insole. The temporary fastenings whereby the insole is attached to the last bottom are then removed, and a middle sole of substantially the same construction as the extension insole 10 is secured to the shoe. From this point the shoe 30 is manufactured substantially as above described with reference to the manufacture of the two-sole construction.

35 It is to be understood that the order in which the lasting operations are performed is immaterial to the present invention. If desired the toe lasting operation may be performed before lasting the sides and heel end of the shoe.

40 It is also to be understood that it is immaterial to the present invention in certain aspects thereof, in what manner the pulling-over operation is performed. If desired it may be performed by means of hand pincers or the lasting strip 16 may be relied upon to pull over the upper and last its toe end in one operation.

45 Having thus described my invention, what I claim as new and desire to secure by Letters Patent of the United States is:

1. That method of making shoes which comprises assembling on a last shoe parts including 50 an upper and an extension sole provided with a toe lasting member, positioning the lasting member above the toe end of the upper and wiping the lasting member over the toe end of the upper in order to shape the upper to the last.

55 2. That method of making shoes which comprises assembling on a last shoe parts including an upper and an extension sole combined with a lasting strip extending forwardly from the region of the tip line and arranged for wiping engagement with the toe end of the upper, positioning the lasting member substantially in the plane of the tip line of the upper, and wiping the lasting member over the toe end of the upper in order to shape the upper to the last.

60 3. That method of making shoes which comprises assembling on a last shoe parts including an upper and an extension sole combined with a toe-lasting member, positioning the lasting member substantially in the plane of the tip line of the upper, stretching the upper over the last, and wiping the lasting member over the toe end of the upper in order to shape the upper to the last.

65 4. That method of making shoes which comprises assembling on a last shoe parts including 70 75

an upper and an extension sole combined with a lasting strip which is formed from the marginal portion at the toe end of the sole blank by severing said marginal portion from the body portion

5 of the blank while leaving it attached to the unsevered margin of the blank in the region of the tip line, positioning the lasting member substantially in the plane of the tip line of the upper, stretching the upper over the last, and wiping 10 the lasting member over the toe end of the upper in order to shape the upper to the last and to hold it in lasted condition.

5. That method of making stitchdown shoes which comprises assembling on a last shoe parts 15 including an upper and an extension sole the upper surface of which at its toe end has the same outline as the bottom of the toe end of the last, stretching the upper lengthwise and widthwise of the last by applying a pull at the forepart, 20 and temporarily attaching its margin at the toe end to the bottom of the sole.

6. That method of making stitchdown shoes which comprises assembling on a last shoe parts including an upper and an extension sole combined 25 with a toe-lasting strip extending from the region of the tip line at one side of the shoe around the toe end of the extension sole to the region of the tip line at the opposite side of the shoe, positioning the lasting strip above the toe 30 end of the upper, stretching the upper over the last and holding it in stretched condition during the interval between said stretching operation and the toe lasting operation, wiping the lasting strip over the toe end of the upper in order to 35 shape the upper to the last, and turning the margin of the upper outwardly under the lasting strip.

7. That method of making stitchdown shoes which comprises assembling on a last shoe parts 40 including an upper and an extension sole combined with a toe lasting member extending from the region of the tip line at one side of the shoe around the toe end of the extension sole to the region of the tip line at the opposite side of the shoe, positioning the lasting member substantially 45 in the plane of the tip line, stretching the upper over the last, drawing the margin of the toe end of the upper over upon the margin of the extension sole and temporarily attaching it there- 50 to, wiping the lasting member over the toe end of the upper in order to shape the upper to the last, detaching the margin of the upper from the extension sole, turning the margin of the upper outwardly under the lasting member, and securing 55 the upper to the extension sole.

8. That method of making stitchdown shoes which comprises assembling on a last shoe parts including an upper and an extension sole the upper surface of which at its toe end has the 60 same outline as the bottom of the toe end of its last, the toe end of the extension sole having a beveled margin extending outwardly from the edge of the last for the reception of fastening means, said extension sole being combined with 65 a toe lasting strip extending from the region of the tip line at one side of the shoe around the toe end of the extension sole to the region of the tip line at the opposite side of the shoe, positioning the lasting member substantially in the plane 70 of the tip line, stretching the upper over the last, wiping the lasting member over the toe end of the upper in order to shape the upper to the last,

turning the margin of the upper outwardly under the lasting member, and securing the toe end of the upper to the beveled margin of the extension sole.

9. That method of making shoes which comprises assembling a lined upper on a last, lasting the lining over the margin of an insole on the last bottom, attaching to the shoe bottom an extension sole a portion of which is slit along a line which registers with the edge of the last bottom, lasting a portion of the upper through said slit, and turning the upper outwardly and securing it to the marginal portion of the extension sole.

10. That method of making shoes which comprises assembling on a last shoe parts including an upper and an extension sole combined with a lasting strip extending forwardly from the region of the tip line and arranged for wiping engagement with the toe end of the upper, positioning the lasting member above the toe end of the upper, wiping the lasting member over the toe end of the upper in order to shape the upper to the last, lasting the margin of the lining over an insole on the last bottom, and turning the everlasting margin of the upper outwardly from the last.

11. As a step-product, a pulled-over stitchdown shoe having an extension sole the edge face of which at its toe end only is in registration with the corresponding edge of the bottom of its last, a shoe upper stretched lengthwise and widthwise of the last, the margin of the upper at its toe end extending inwardly of the shoe bottom while the remainder of the margin extends outwardly of the shoe bottom.

12. As a step product, a lasted stitchdown shoe having an extension sole the toe portion of which is provided with an outwardly beveled margin, the upper surface of the toe portion of said extension sole having substantially the same outline as the bottom of the toe portion of the last, the toe portion of the upper being fastened to the beveled margin of the extension sole and turned outwardly therefrom.

13. As a step product, a lasted stitchdown shoe having an extension sole the toe portion of which has substantially the same outline as the bottom of the toe end of the last, the toe portion of said sole being provided with a welt formed from the sole blank, the outturned margin of the toe portion of the upper being lasted to the bottom face of said welt while the outturned margin rearwardly of the toe portion of the upper is lasted to the top of the sole margin.

14. As a step product, a lasted stitchdown shoe having an extension sole the toe portion only of which is provided with an outwardly beveled margin, the upper surface of the toe portion of said sole having substantially the same outline as the bottom of the toe portion of the last, said extension sole being provided with a welt formed from the sole blank and extending around the toe portion of the sole, the outturned margin of the toe portion of the upper being lasted to the bottom face of said welt and fastened to the beveled margin of the toe portion of the sole while the outturned margin rearwardly of the toe portion of the upper is lasted to the top of the outwardly extending margin of the extension sole.
